US0D1025357S

(12) **United States Design Patent** (10) Patent No.: **US D1,025,357 S**
(45) Date of Patent: ** Apr. 30, 2024

(54) **TATTOO MACHINE**

(71) Applicant: **FK Irons Inc.**, Doral, FL (US)

(72) Inventors: **Gaston Alfonso Siciliano**, Bal Harbour, FL (US); **Helber Ivan Tovar**, Hialeah Gardens, FL (US); **Lester Perez Pineiro**, Hialeah, FL (US)

(73) Assignee: **FK Irons Inc.**, Doral, FL (US)

(**) Term: **15 Years**

(21) Appl. No.: **29/809,979**

(22) Filed: **Sep. 30, 2021**

(51) LOC (14) Cl. **24-02**

(52) U.S. Cl.

USPC **D24/144**

(58) **Field of Classification Search**

USPC D24/144, 146–147, 133, 170
CPC A61M 37/0076; A61M 37/0084; A61M 37/0092; A61M 5/48; A61M 5/482; A61M 37/00

See application file for complete search history.

(57) **CLAIM**

The ornamental design for a tattoo machine, as shown and described.

DESCRIPTION

FIG. 1 is a perspective view of a tattoo machine showing our new design;

FIG. 2 is a front view thereof;

FIG. 3 is a rear view thereof;

FIG. 4 is a right side view thereof;

FIG. 5 is a left side view thereof;

FIG. 6 is a bottom view thereof; and,

FIG. 7 is a top view thereof.

The broken lines in the drawings depict portions of the tattoo machine and form no part of the claimed design.

1 Claim, 7 Drawing Sheets
